CLAIM

The ornamental design for an interface for a display screen for an electronic device, as shown and described.

DESCRIPTION

FIG. 1 is a front view of an interface for a display screen for an electronic device;

FIG. 2 is a front view of a second embodiment thereof; FIG. 3 is a front view of a third embodiment thereof; and, FIG. 4 is a front view of a fourth embodiment thereof.

The broken line disclosure of a display screen for an electronic device in FIGS. 1-4 is for illustrative purposes only and forms no part of the claimed design.
